Issued June 28 1870

United States Patent Office.

GEORGE W. DOWNING, OF NEW YORK, N. Y., ASSIGNOR TO THE REDFIELD AND RICE MANUFACTURING COMPANY, OF SAME PLACE.

Design No. 4,218, dated July 12, 1870.

DESIGN FOR HANDLES OF SPOONS, FORKS, LADLES, &c.

The Schedule referred to in these Letters Patent and making part of the same.

To all whom it may concern:

Be it known that I, GEORGE W. DOWNING, of the city, county, and State of New York, have invented a new and original Design for the Handles of Spoons, Forks, Knives, Ladles, &c.; and I do hereby declare that the following is a full, clear, and exact description thereof, which will enable others skilled in the art to make and use the same, reference being had to the accompanying drawing forming part of this specification, in which the figure represents my improved design, as applied to a spoon-handle.

My invention has for its object to furnish a new and original design for the handles of spoons, forks, knives, ladles, and other articles forming table-sets,

which shall be neat, simple, appropriate, and ornamental, and it consists in the design which is fully represented in the accompanying drawing.

Having thus described my invention,

I claim as new and desire to secure by Letters Patent—

The design for the handles of spoons, forks, knives, ladles, &c., substantially as shown.

The above specification of my invention signed by me this 15th day of June, 1870.

GEORGE W. DOWNING.
